(57) **CLAIM**

The ornamental design for a power connector, as shown and described.

DESCRIPTION

FIG. 1 is a front perspective view of a power connector showing my new design;

FIG. 2 is a back perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The outmost broken lines immediately adjacent to the full line showing of the claimed design represent the bounds of the claimed design while all other broken lines are directed to environment and are for illustrative purpose only; the broken lines form no part of the claimed design.

1 Claim, 8 Drawing Sheets

FIG. 1

FIG. 2

FIG. 3

FIG. 4

FIG. 5

FIG. 6

FIG. 7

FIG. 8
